UNITED STATES PATENT OFFICE.

FELIX SAMSON, OF NEW YORK, N. Y.

DESIGN FOR NAP-SURFACE OF CLOTHS.

SPECIFICATION forming part of Design No. 12,184, dated March 8, 1881.

Application filed January 21, 1881. Term of patent 7 years.

To all whom it may concern:

Be it known that I, FELIX SAMSON, of New York city, New York, have originated a novel Design for the Nap-Surface of Cloths, of which 5 the following is a full, clear, and exact description in connection with the accompanying drawings.

This design is related to that class of figurings which are produced on the nap-surface of 10 the heavier kinds of cloth by cutting distinct grooves thereinto in the act of "shearing" or finishing the nap, so as to leave the figures in sharp relief; and my design consists in a particular figuring of this character, as hereinaf- 15 ter fully set forth.

In the annexed drawings, which clearly illustrate my design, Figure 1 is a face view of 20 a piece of cloth embodying this design, and Fig. 2 a cross-section. These views show the design enlarged about one-third more than the size I intend to practically use; but the scale of the design may, of course, be varied according to the thickness of the cloth, or to the kind of cloth on which the design is used.

25 It may be seen from the drawings that the general or extreme surface of the cloth is finished smooth, or nearly so, but that this surface is indented with a series of grooves, which grooves are cut into the pile or nap of the 30 cloth, in the act of shearing the same, with cutters specially formed therefor in the usual manner. It will now be seen that these grooves run diagonally across the cloth and in parallel lines; but instead of being continuous, as is 35 commonly the case, the grooves abruptly terminate in short sections at regular intervals,

and are thus disposed in parallel bands *a a*, which are separated by straight or vertical lines *b b* of the smooth or level part of the nap.

The diagonally-grooved bands *a a* may be of 40 uniform width alternately with the level lines or stripes *b b*; but the grooved bands are preferably made alternately narrow and wide, as illustrated, as the ornamental effect is thereby increased.

45 This design, as may be now observed, is distinct from the usual continuous diagonal lining, and in being cut into the cloth presents a sharper and more striking effect, while the bands of diagonal grooves, alternating with 50 the vertical level lines or stripes, diversify the effect and give a more novel and pleasing tone to the figuring.

What I claim is—

1. The described design for the nap-surface 55 of cloth, consisting of a series of short diagonal grooves cut into the nap or pile of the cloth, and disposed in parallel bands separated by lines or stripes of smooth or level nap, substantially as herein illustrated.

60 2. The specified design for the nap-surface of cloth, consisting of a series of short diagonal grooves in the nap or pile of the cloth, disposed in parallel bands, alternately wide and narrow, and separated by vertical lines or 65 stripes of smooth or level nap, substantially as herein illustrated.

FELIX SAMSON.
